Patented July 31, 1917.

Inventor:

Charles F. Elmore
By Leoratus S. Bellows

Attorney:

UNITED STATES PATENT OFFICE.

CHARLES F. ELMORE, OF CHICAGO, ILLINOIS.

DESIGN FOR AN EMBLEM.

51,094.

Specification for Design.

Patented July 31, 1917.

Application filed June 11, 1917. Serial No. 174,150. Term of patent $3\frac{1}{2}$ years.

To all whom it may concern:

Be it known that I, CHARLES F. ELMORE, citizen of the United States, residing at Chicago, in the county of Cook and State of Illinois, have invented a certain new, original, and ornamental Design for an Emblem, of which the following is a specification.

In the accompanying drawing which forms a part of this specification the figure is a front elevation showing an emblem illustrating my new design.

I claim:

The ornamental design for an emblem, as shown.

CHARLES F. ELMORE.
